UNITED STATES PATENT OFFICE.

CHARLES H. HOLDREDGE, OF STONINGTON, CONNECTICUT.

AUTOMATIC INK-WELL.

1,228,921.

Specification of Letters Patent. Patented June 5, 1917.

Application filed January 13, 1917. Serial No. 142,266.

To all whom it may concern:

Be it known that I, CHARLES H. HOLDREDGE, a citizen of the United States, residing at Stonington, in the county of New London and State of Connecticut, have invented certain new and useful Improvements in Automatic Ink-Well, of which the following is a specification, reference being had to the accompanying drawings.

10 This invention relates to ink wells and particularly to that class of ink wells wherein provision is made for normally covering the ink except for a small aperture so that the ink will not evaporate.

15 The object of my present invention is to provide a very simple, cheaply made and effective form of ink well which is so constructed that a slight thrust of the pen against the surface of a floating member 20 will cause the depression of the floating member, this floating member being so formed as to retain a relatively small but sufficient amount of ink upon its upper surface.

25 A further object of the invention is to provide an ink well having therein a floating disk having at its middle a barrel extending down into the ink, and provide within this barrel a float having at its upper 30 end a slight depression so that the touch of the pen will cause the float to sink, the float then rising up to its original position with a pen full of ink.

35 Other objects will appear in the course of the following description.

My invention is illustrated in the accompanying drawings, wherein,

Figure 1 is a vertical sectional view of an ink well constructed in accordance with my 40 invention;

Fig. 2 is a top plan view of the ink well shown in Fig. 1.

Referring to these figures, it will be seen that I have provided an ink well designated 45 generally 11 and which may be made of any suitable form but which is provided with a cap 12 fitted over the upper end of the ink well and having a forwardly extending flange 13 projecting inward beyond the wall 50 of the ink well. Resting upon the surface of the ink and floating thereon is a member 14 which is annular in form and has downwardly extending side flanges 15. This member 14 is dish-shaped or concavo-convex, 55 the convex surface facing toward the bottom of the ink well. This member 14 has a diam-

eter greater than the inside diameter of the annular flange 13. This member 14 rests upon the surface of the ink and floats thereon and, as the ink is used up, moves 60 downward within the ink well. The member 14 carries upon it the downwardly extending barrel 16 which is open at its bottom and top and disposed within this barrel is a float 17 which may be made of wood or 65 other buoyant material or may be made hollow and of glass, vulcanite, or other like material. The outer surface of this float is formed with a depression 18 which is of such depth and diameter as to contain a drop or 70 more of ink sufficient to fill a pen point. Preferably a bail 19 is attached to the barrel which extends beneath and limits the downward movement of the float 17. This bail is 75 preferably formed of very small wire and is swingingly mounted upon the barrel.

The operation of the invention will be obvious from what has gone before. Normally the float 17 has its upper surface approximately just below the upper surface of the 80 member 14. When it is desired to secure ink, the pen is thrust into the ink well and a touch of the pen upon the float 17 causes the latter to move downward and the ink to rise up and flow into the depression 18 so that a 85 pen full of ink is presented to the pen. It will be seen that only a very small part of the ink is submitted to evaporation so that the ink will not be wasted and will not dry up within the ink well. The device does not 90 readily get out of order nor clog. It is very simple, may be cheaply constructed, and may have a certain ornamental value. The body of the well is formed with a deep recess in its bottom to permit the full depression of 95 the floating disk 14.

It will thus be seen that a relatively small amount of ink is always present in the mouth or opening of the floating annulus but that at the same time the ink is prevented from evaporating at any rapid rate. It will be seen that a drop of ink or a small portion of ink will be disposed at all times in such position as to be readily taken up by the pen in both forms of my device.

Having described my invention, what I claim is:

1. In an ink well, a floating member disposed within the well and adapted to float upon the top of the ink, said member being 110 annular in form to provide a central opening and having a downwardly extending

wall surrounding said opening but spaced therefrom, a float disposed within the space surrounded by the wall and having a central depression at its upper end, the upward movement of the float being limited by the projection of the annular member inward beyond the wall, and a bail swingingly mounted upon the barrel extending beneath it and limiting the downward movement of the float, said bail being movable out of the way of the float to thereby permit the float to be removed from the barrel.

2. In an ink well, a floating member disposed within the well and adapted to float upon the top of the ink, said member being annular in form to provide a central opening and said member having an annular wall extending downward from the member concentric to the central opening and defining a

chamber open at its lower end, and having 20 a uniform diameter from top to bottom, the wall being spaced from the central opening, a float disposed within the space surrounded by the wall and having a central depression at its upper end, the upward movement of 25 the float being limited by the projection of the annular member inward beyond the wall, and means normally preventing the depression of the float below the lower end of said annular wall, but shiftable out of the path 30 of movement of the float to thereby permit the removal of the float.

In testimony whereof I hereunto affix my signature in the presence of two witnesses.

CHARLES H. HOLDREDGE.

Witnesses:

WILLIAM A. WILCOX,
ALBERT G. MARTIN.
